PREPARATION OF SATURATED
HYDROCARBONS

Harold T. Quigg, Bartlesville, Okla., assignor to
Phillips Petroleum Company, a corporation of
Delaware

Application July 24, 1945, Serial No. 606,868

11 Claims. (Cl. 260—683.4)

1 This invention relates to the preparation of paraffins or saturated hydrocarbons from low-boiling normally gaseous olefins, and especially from ethylene or ethylene and propylene, contained in normally gaseous streams such as the effluent from an ethane and/or propane cracking unit or the cracked gas formed as a by-product in cracking operations. More particularly it relates to the conversion of such low-boiling aliphatic olefins into higher-boiling paraffins in the motor and/or aviation fuel range of boiling point and molecular weight. Still more particularly, it relates to a process wherein the ethylene contained in cracked gas streams is converted to valuable paraffinic hydrocarbons, especially branched chain octanes, suitable for use as a high knock rating blending component in the preparation of aviation and motor fuels.

The art of converting butylenes, by alkylation of isoparaffins especially isobutane, to high octane hydrocarbons is well known. It is also well known that the conventional alkylation catalysts such as hydrofluoric acid and sulfuric acid will not effect alkylation with ethylene. Special catalysts such as aluminum chloride are required to bring about alkylation of isoparaffins with ethylene. The alkylation of isobutane with ethylene by means of aluminum chloride-containing catalysts produces C₈ hydrocarbons, especially diisopropyl. However, no economically feasible process is available whereby aliphatic olefins boiling below butylenes, such as propylene and more especially ethylene, can be reacted with isoparaffins to give paraffins heavier than C₇, such as the branched chain octanes, nonanes and higher paraffins. Since tremendous quantities of ethylene and propylene are cheaply and readily available in dilute form in cracked gas streams, such a process is highly desirable.

The principal object of my invention is to make available to the art a process whereby low-boiling olefins, especially propylene and more particularly ethylene, can be converted to heavier saturated hydrocarbons of motor and aviation fuel and heavier boiling range, predominantly C₈ and heavier, in a simple and economical manner. Another object is to provide a process of the foregoing type which involves a minimum number of steps and gives a high yield of valuable products with a minimum of loss by undesirable side reactions and the like. Another object is to provide an improved method of converting olefins contained in waste refinery gas streams into valuable products. Another object is to provide a process of the foregoing type which gives

2 a high yield of high octane number C₈ and heavier hydrocarbons from an olefin-containing stream which contains relatively small amounts of propylene. Another object is to provide a process as in the foregoing objects which does not require an expensive preliminary concentration of ethylene or ethylene and propylene contained in the cracked gas stream used as starting material. Another object is to provide a process of the foregoing type which gives a more desirable product than is obtained from other processes using light olefins, such as ethylene, as the raw material. Numerous other objects will appear more fully hereinafter.

15 The accompanying drawing portrays diagrammatically one arrangement of equipment which has been found suitable for carrying out the process of the present invention.

General

In accordance with my invention, normally gaseous olefins contained in a normally gaseous mixture containing other normally gaseous components, especially hydrogen and paraffins including methane, are converted into heavier hydrocarbons in the motor and aviation fuel range of molecular weight and boiling point by three sequential steps which are integrated into a unitary process. The olefins are first removed from the normally gaseous feed mixture by absorption in liquid isoparaffin as an absorption liquid. This dissolves the olefins while allowing the light non-olefinic components, principally hydrogen and methane, to pass through undissolved. The liquid isoparaffin rich in olefin is withdrawn from the absorber and is passed to a catalytic polymerization zone wherein the olefin content is polymerized catalytically with the isoparaffin as a diluent. The ethylene is thereby converted to butylene and if any propylene is present, as is usually the case, ethylene and propylene are inter-polymerized or co-polymerized to give amylenes or pentenes. Ordinarily, the ethylene is present in such excess that the propylene is entirely consumed in this manner, substantially no simple polymerization of propylene to hexylenes taking place. The isoparaffin and the polymer contained in the catalytic polymerization effluent are now fed to an alkylation zone where the isoparaffin is alkylated with the polymers or higher-boiling olefins formed in the polymerization step to give heavier saturated hydrocarbons having a highly branched structure and being in the motor and aviation fuel range of molecular weight and boiling point. Generally, the al-

alkylate produced is mainly composed of C₈ paraffins and heavier. The alkylate formed can be readily separated into a relatively light fraction, suitable for use as a high knock rating blending component of motor and aviation fuels, and a relatively heavy fraction known in the art as "heavy alkylate" which is very suitable for use as a "safety fuel," as solvent in paints, varnishes, lacquers and other plastic and coating compositions, in dry-cleaning, or in insecticides such as fly sprays, etc.

Thus it will be seen that the isoparaffin serves first as an absorption liquid to remove the olefins from the lighter fixed gases, hydrogen and methane, then as a diluent in the polymerization step whereby undesirable side reactions are prevented in the polymerization zone, and then as one of the reactants, namely, the hydrocarbon which is alkylated in the alkylation step. No separation of olefins from the rich absorption medium leaving the absorber is required before the polymerization step and the effluent from the polymerization step is a suitable feed to the alkylation step requiring only the removal of unreacted light gas.

Feed stocks

As the olefin-containing gas stream fed to my process, I prefer to use any stream rich in ethylene. The feed may or may not contain propylene. The gas may be from any source, for instance the waste gas formed in the cracking of heavier normally liquid material such as gasoline, naphtha, kerosene, gas oil, fuel oil, crude oil, or the like. The cracking gas obtained from vapor phase cracking processes is especially rich in olefins which often range up to 60 per cent of the total gas and of which ethylene is predominant. The methane and hydrogen content may range from 25 to 50 per cent of the cracking gas. The composition of cracking gases is discussed on pages 114-116 of vol. 1 and pages 139-140 of vol. 2 of Ellis, "The Chemistry of Petroleum Derivatives." Ordinarily, such cracking gas is subjected to known treatment for the removal of the valuable C₄ and heavier components and frequently even the C₃ components prior to its use as feed to the process of the present invention. The feed to the present invention may be derived from the cracking of ethane or propane or mixtures of ethane and propane which, as is now well-known, yields an ethylene-rich gaseous effluent which usually contains a substantial amount of propylene as well as of material heavier than C₃ hydrocarbons. Such an effluent is commonly treated to remove the C₄ and heavier material and if desired the C₃ content thereof, although I often prefer to use a feed from which the propylene has not been removed.

A typical cracking gas stream obtained in the cracking of gas oil had the following analysis:

Gas volume per cent	
Hydrogen	4.0
Methane	33.7
Ethane	23.2
Ethylene	3.0
Propane	17.5
Propylene	5.7
Butanes	9.9
Butenes	2.7
Pentenes	0.3

Such a stream after extraction of the C₄ and heavier components, which extraction may also remove a part or all of the C₃ components if de-

sired, is suitable as feed stock for the present invention.

A typical gas obtained by cracking a 25% ethane-75% propane mixture at 6-8 p. s. i. g. and at 1400° F. followed by extraction of C₄ and any heavier hydrocarbons had the following analysis:

	Mol per cent
Hydrogen	18
Methane	38
Ethane	11
Ethylene	29
Propane	0.5
Propylene	3.5

Such a stream is an excellent feed for the process of the present invention.

The other feed to the process of the present invention is an isoparaffin feed. Usually this is a stream of isobutane since isobutane upon alkylation with the lowest polymer of ethylene, namely butylene, or with the inter-polymer of ethylene and propylene, the polymers formed from the olefins contained in the preferred olefin stream, gives isoctane and other highly branched octanes, nonanes, etc., which are valuable motor and aviation fuel blending components and for other purposes wherever "heavy alkylate" is desired. However, the feed may comprise isopentane or even isohexane. It may be a mixture of isobutane and isopentane. Use of such higher isoparaffins gives a greater yield of "heavy alkylate." Normal paraffins corresponding to the isoparaffins may be present in the isoparaffin feed. For example, the presence of substantial quantities of normal butane in the isobutane feed stream is unobjectionable since such normal butane functions as an absorbing liquid in the first or absorption step and as an inert diluent reducing side reactions in the polymerization step and in the alkylation step. The pressure of excessive amounts of normal paraffin in the isoparaffin feed may be undesirable because it is not feasible to eliminate the normal paraffin prior to the alkylation step and the presence of a large amount of normal paraffin may undesirably repress the desired alkylation reaction.

Both feed stocks should be free of contaminants or impurities which would interfere with the polymerization or alkylation reactions or which would be objectionable in the finished product. In general, the feeds are essentially free from sulfur, nitrogen and oxygen compounds. For example, the feed stocks should be free from sulfur or sulfur compounds such as hydrogen sulfide, mercaptans, alkyl sulfides, etc. since these impurities are objectionable both in the catalytic conversions and in the product.

Absorption step

In the first step of the process of my invention, the olefins contained in the feed, which olefins usually consist of ethylene or of a mixture of ethylene and propylene with the ethylene often in excess of the propylene, are absorbed in liquid isoparaffin, generally isobutane, while the fixed gases, which usually consist of hydrogen and methane pass through undissolved. Since the absorption is not selective for olefins as against paraffins, but is based merely on relative volatility of the several hydrocarbons present, ethane and any propane present in the feed are dissolved along with ethylene and any propylene. However, the presence of these paraffins in later portions of the process is not objectionable; on the

contrary, they serve as desirable inert diluent in addition to the isoparaffin in the subsequent polymerization step. Generally, they are removed with other C₃ and lighter components between the polymerization step and the alkylation step.

The absorption step may be a simple gas scrubbing operation conducted in the usual vertical column packed or provided with other means for effecting the desired intimacy of contact such as the usual bubble trays, the cold liquid isoparaffin such as isobutane being injected continuously at a point near the top of the tower and descending downwardly therein in countercurrent to the gaseous olefin-containing feed introduced adjacent the bottom, the undissolved hydrogen and methane continuously passing out overhead and the rich absorbing liquid being continuously withdrawn from the bottom of the column. With such an arrangement the absorber pressure and the temperature and rate of introduction of isoparaffin are so adjusted as to effect solution of substantially all the olefins with minimum loss of valuable hydrocarbons (C₂ and heavier including isoparaffin absorbent) in the overhead or residue gas. Where isobutane is used as the isoparaffin, the pressure in the absorption zone may range from 700 to 800 pounds per square inch gauge, the overhead temperature may be below 40° F., for example, 30° F. or therebelow, and the rate of introduction of liquid isobutane into the top of the absorber may be such as to give a mole ratio of isobutane fed in to olefin in the feed ranging from 2:1 upwardly say to 50:1, a range of from 2:1 to 10:1 being preferred.

I prefer to provide means for at least partially condensing the overhead from the absorber and returning liquid condensate to the top of the column as liquid reflux therefor in addition to the reflux effect provided by the fresh isoparaffin injected thereto. By condensation of overhead vapors the loss of isoparaffin in the outgoing residue gas is cut to a minimum. The condensation should be sufficient to liquefy substantially all vaporized isoparaffin; for example, where the isoparaffin is isobutane the condensation is so carried out as to liquefy substantially all the isobutane from the overhead gases. If it is found suitable or desirable, the condensation may extend down to the C₃ hydrocarbons and in extreme cases even down to the C₂ hydrocarbons but the expense of refrigeration requirements to condense the C₂'s is prohibitive at the present time and the condensation of the C₃'s is often not commercially feasible under present-day conditions. The condensation of the condensable hydrocarbons from the overhead gases may be carried out in any suitable way as by providing indirect cooling coils in the top of the absorber, or by cooling the overhead in a separate cooler, passing to a condensate or reflux accumulator from which the uncondensed gases are vented in the usual way, and withdrawing the liquid condensate and injecting it into the top of the absorber.

In many cases I prefer to operate the absorber as an "extractive distillation" column, i. e., to combine rectification and absorption by providing means for reboiling the kettle product prior to its withdrawal and means for partially condensing the absorber overhead as just described. The principles underlying extractive distillation are now well understood by those skilled in the art and need not be detailed herein. When extractive distillation is employed for separating the olefins from the methane and hydrogen in practicing my invention, the olefin-containing feed is in-

roduced into the middle of the absorber column rather than into its bottom as in the case where simple gas scrubbing is practiced. In extractive distillation the bottom temperature will be the boiling point of the kettle product at the column operating pressure.

Polymerization step

The isoparaffin containing dissolved olefin withdrawn from the absorber as bottom or kettle product is next passed to a unit wherein the olefins are polymerized to higher-boiling olefins. The isoparaffin functions as an inert diluent and to repress undesired side reactions during the polymerization, and also to enable liquid phase conditions to be maintained therein without excessive pressures and even though the polymerization temperature be above the critical temperature of the ethylene or of the ethylene and propylene.

It is preferred to conduct the polymerization under such conditions that substantially the sole reaction is one of simple polymerization of the olefin. It is also preferred that conditions be so adjusted that a major portion of the olefin polymer produced is in the C₄-C₈ range. For example, where the olefin consists substantially of ethylene, it is preferred that the polymerization convert it principally to butylene and where the olefin consists essentially of ethylene and propylene that principally butylene and amylene be formed. Since the propylene is usually present in minor amount, conversion thereof to amylene by co-polymerization, mixed polymerization or inter-polymerization with the ethylene which is present in excess, is relatively easily accomplished. Where propylene is in excess of ethylene the excess may be converted to the dimer.

Polymerization primarily to olefin in the C₄-C₈ range is preferred in order that upon alkylation of the isoparaffin with the polymer the alkylate will not be unduly heavy but instead will be primarily in the gasoline range. To this end, polymerization conditions are so adjusted as to effect principally dimerization and simple co-condensation of ethylene with propylene. If production of heavy alkylate as the principal or sole product is desired then polymerization of the olefin to higher olefins than C₈ may be effected. However, ordinarily the extreme upper limit of polymer range will be decylene since alkylation of the usual isoparaffin with olefin polymer above decylene gives alkylate having more than 14 carbon atoms per molecule for which there is little demand.

The polymerization is conducted catalytically. The selection of suitable catalysts and suitable reaction conditions such as pressure, temperature, contact time, ratio of hydrocarbon to catalyst, and other factors will be obvious to those skilled in the art in the light of this disclosure. In general, the polymerization of ethylene requires somewhat more active catalyst or more drastic reaction conditions than the polymerization of its homologs. I prefer to effect polymerization of the ethylene by means of a more active catalyst which effects the desired conversion under conditions such that, with the isoparaffin present in amount required to effect the absorption, a minimum of side reactions takes place in the polymerization zone. A catalyst which I have found to be exceptional is that of activated nickel oxide supported on a suitable carrier as disclosed more fully in the copending applications of G. C. Bailey et al., Ser. No. 435,888,

filed March 23, 1942 (now U. S. Patent 2,381,198 granted August 7, 1945), and Ser. No. 599,536, filed June 15, 1945. The patent applications mentioned are directed particularly to the catalytic polymerization of ethylene and the disclosures thereof are hereby incorporated by reference. A preferred carrier is that disclosed in the second-mentioned application, namely, silica gel either by itself or preferably promoted with a small amount of alumina as by impregnating the still wet or only partially dried freshly precipitated silica gel with an aqueous solution of a suitable aluminum salt such as aluminum sulfate or nitrate. Use of supported nickel oxide catalysts of the types disclosed in the above mentioned applications is especially advantageous in the practice of this step of my invention because such catalysts smoothly effect simple polymerization of ethylene which very frequently is the sole or the principal olefin present in the feed.

The polymerization temperature may vary within a rather wide range but will generally not be much lower than about 0° C. nor substantially above about 225° C. It is preferred to polymerize with the range of about 50 to 150° C. Atmospheric temperature, about 24° C., is often used. Temperatures of at least about 100° C. ranging up to 200° C. may be superior since at such levels polymerization is accelerated without undue side reactions. Above a polymerization temperature of about 200° C. hydrocarbons other than olefin polymers begin to be formed. The polymerization is ordinarily conducted at temperatures not over 150° C. It is carried out in the absence of hydrogen or other reducing agent.

High pressures favor the polymerization reaction, but under suitable conditions the reaction may be carried out under a very wide range of pressures, from as low as atmospheric or below to as high as 2000 p. s. i. or above. Although high pressures increase the rate of polymerization they also increase the average molecular weight of the polymer formed. Accordingly, it is ordinarily preferred to conduct the polymerization at temperatures of not over 200 p. s. i.

The polymerization may be carried out in either liquid or gas phase. Ordinarily liquid phase operation is preferred. Accordingly, the presence of the isoparaffin in the feed to the polymerization step is additionally advantageous since it enables liquid phase conditions to be maintained much more readily and at desirably moderate pressures. Pressures such as to insure substantial or complete liquid phase operation are preferred. Liquid phase operation facilitates control of reaction temperature and contributes to catalyst life by diminishing the deposition of high molecular weight, or other non-volatile or insoluble, materials on the catalyst surface. When polymerizing at temperatures above the critical temperature of the olefin, the presence of the inert isoparaffin, which was used as an absorbing liquid and is subsequently used as the alkylated hydrocarbon, facilitates the maintenance of liquid phase conditions. When polymerizing at temperatures below the critical of the olefin, the isoparaffin performs its functions of minimizing side reactions and serving as an inert diluent.

In the relatively rare situation where polymerization is carried out with the hydrocarbons in the gas phase, conditions should be such that the exothermic heat of reaction does not cause excessive local overheating of the catalyst or a general rise in temperature above the desired op-

erating range. This can be accomplished by suitable design of a catalyst chamber to allow good heat transfer, and by controlling the rate of introduction of charge stock.

The contact time in the polymerization zone may vary over a wide range. A time as low as 30 seconds at atmospheric pressure and in the preferred temperature range is sufficient to polymerize the olefins appreciably. However, higher extents of conversion are possible when a longer contact time and/or higher pressure are utilized. Contact times of 3 and even 12 hours may be employed but are ordinarily too long to be commercially feasible. Contact times sufficient to polymerize at least 75% of the olefin are preferred in order to minimize recycle or auxiliary polymerization.

Since the preferred nickel oxide catalysts are readily deactivated or poisoned by various materials such as sulfur compounds, carbon monoxide, some halogen compounds, organic oxygen-containing compounds, and the like, it is desirable, in order to secure satisfactory catalyst life, to exclude such materials from the polymerization system. This is preferably done by excluding them from the feeds to the absorbing step. Any suitable means for removing such materials from the feed may be employed.

Where the polymerization catalyst is a solid material it may be arranged in the form of a bed through which the polymerization feed is passed, usually downwardly. Alternatively, the catalyst may be suspended in the hydrocarbon liquid or vapors in the manner in which so-called "fluid" catalytic conversions are effected. Known means for regenerating the catalyst is provided regardless of the form which the catalyst takes.

Instead of a nickel oxide catalyst, I may use any other catalyst which is capable of effecting the polymerization of ethylene. Such other catalysts may be either known now or discovered in the future. The reaction conditions discussed in detail above apply particularly to the preferred activated nickel oxide catalyst. With other catalysts different polymerization conditions may be desirable. As an example of another type of catalyst, I may use boron fluoride and a nickel promoter as disclosed in Otto et al. 1,989,425. Another catalyst is aluminum chloride.

The effluent from the polymerization step may be subjected to fractionation or other means of separation to remove all material lighter than C₄ leaving a fraction containing C₄ and heavier including isoparaffin and butylene and all other polymeric material formed in the polymerization step. If desired it may be further fractionated to separate material heavier than a predetermined level of molecular weight or boiling point. For example, if the polymerization produces a small amount of heavy oily or waxy polymers it is often desirable to remove these and thereby prevent them from entering the alkylation step where they would give undesirably heavy alkylate. The unpolymerized olefin separated from the polymerization effluent may be passed to an auxiliary polymerization unit and there polymerized catalytically, the resulting polymer being merged with the polymer from the main polymerization unit for passage to the alkylation step. If desired, isoparaffin may be admixed with the olefin feed to the auxiliary polymerization unit whereby the above-detailed advantages of its presence in the main polymerization unit are attained. If desired the olefin-containing stream separated from the main polymerization effluent

may be recycled to the absorption step or directly to the main polymerization step.

Alkylation step

The last major step of my process is that wherein the isoparaffin is alkylated with the olefin polymers formed in the polymerization step to give higher-boiling branched-chain paraffin hydrocarbons having at least eight carbon atoms per molecule and ranging from the gasoline boiling range up through "heavy alkylate" ordinarily having not more than fourteen carbon atoms per molecule.

The alkylation step is conducted in a manner known per se. It is almost invariably carried out catalytically. It is ordinarily preferable to employ an inorganic acid such as substantially anhydrous hydrofluoric acid or concentrated sulfuric acid as the alkylation catalyst although any other suitable alkylation catalyst known now or discovered in the future may be employed, since the alkylation step does not per se constitute my invention. Many other alkylation catalysts are known such as aluminum chloride, aluminum chloride complexes, boron fluoride, etc.

The alkylation step is conducted in a manner well within the present skill of the art and conditions for this step need not be described in detail. Suffice it to say that the alkylation is conducted in such a way that the olefins alkylate the isoparaffin to give the desired product.

The alkylation effluent is treated in known manner as by fractionation, etc. to recover recycle and product streams. Usually a phase of catalyst is recovered for recycle to the alkylation unit, a portion being passed to a regeneration or re-run unit. Likewise a phase of unreacted isobutane is recovered for recycle to the absorption unit.

Many advantages are attained by the present invention. The principal advantage is that cheap olefins especially ethylene in readily available cracked gas streams are converted to very valuable alkylate in a simple and economical manner. Other advantages are that a single material, namely, the isoparaffin, performs a number of valuable functions in a simple and peculiarly advantageous manner, namely, as liquid absorbent in the first step, as diluent and liquefying medium in the polymerization step and as major reactant in the alkylation stage. Another advantage is that a large excess of isoparaffin to olefin is maintained in the absorption step and is therefore maintained in the polymerization and alkylation steps whereby very undesirable side reactions are prevented. This large excess of isoparaffin is particularly advantageous in the alkylation step since it prevents olefin polymerization and improves the alkylate quality. Many other advantages of my invention will be apparent to those skilled in the art.

Referring now to the accompanying drawing, the olefin-containing gas stream is charged to an absorber 2 through line 1. The absorber is operated under such conditions (for instance, 30° F. overhead and 760 p. s. i.) that most of the C₂ and heavier hydrocarbons are absorbed in the liquid isobutane supplied at the top of the absorber 2, while lighter hydrocarbons such as hydrogen and methane are removed as gases. Isobutane which will be used in the reaction later is used as the absorption medium and as the reflux for the absorber 2 being added through line 4 in a mole ratio of 2:1 to 50:1 of olefin with a ratio of 2:1 to 10:1 preferred. Absorber 2 may

be provided with a reboiler 2A as shown to effect fractionation, thus serving to effect extractive distillation. If desired, the overhead may be cooled or dephlegmated to condense C₂ and heavier, or C₃ and heavier, or C₄ and heavier which is fed to the top of absorber 2 as reflux. Usually it will be desirable to condense and return only the C₄ (and any heavier) contained in the absorber overhead, to avoid excessive refrigeration requirements. The provision for refluxing the tower is indicated diagrammatically on the drawing by the showing of an indirect reflux cooler 2B, although it will be obvious that any other suitable means for effecting the desired result may be employed. The fixed gases such as hydrogen and methane are removed at 3 and disposed of in any desired manner. The isobutane and absorbed gases are removed through line 5 and charged to polymerization reactor or reactors 6. The reactors 6 may be operated in any desired sequence; two or three reactors 6 may be operated in parallel or series while the other one or two chambers are being regenerated with an oxygen-bearing gas. Ethylene can be converted to predominantly butylenes, and if propylene is present copolymerization to amylenes may also be effected by the use of any suitable catalyst. A preferred catalyst is one of activated nickel oxide on a suitable carrier such as is described in the above-mentioned copending applications of G. C. Bailey et. al., Ser. No. 435,888, filed March 23, 1942 (now Pat. No. 2,381,198), and Ser. No. 599,536, filed June 15, 1945.

The effluent from the polymerization reactor is withdrawn through line 7 and charged to a separator 8 which conveniently takes the form of a conventional fractional distillation column and which is operated under such conditions that C₃ and lighter hydrocarbons are removed through line 9. The disposal of this material will be governed by the amount of olefin present and the value of the olefin. If the olefin content of the gas is low it may be removed through line 25 and disposed of in any manner. If the olefin content of the gas is high a portion of the gas may be returned to the feed to the absorber 2 through line 26 and the remainder vented through line 25 or all of the gas may be charged to an auxiliary polymerization unit 27 similar to 6 but adjusted as to size. The effluent from the polymerization unit 27 is withdrawn through line 28 and charged to a separator or fractionation column 29 from which polymer is removed through line 31 and mixed with the effluent from the separator 8 in line 11. Residue gas from separator 29 is removed through line 30. The isobutane and olefins are withdrawn through line 11 and charged to an alkylation unit 13. Any type alkylation unit may be used such as an HF or sulfuric acid unit operated under conditions known to the art. The effluent from the alkylation unit 13 is charged to a separation unit 15 through line 14. Separation unit 15 may comprise a series of fractional distillation columns to effect the indicated separations. Catalyst carried out with the hydrocarbon may be reclaimed and returned to the reactor 13 through line 16. Excess isobutane is removed through line 17 and may be combined with fresh isobutane through line 32 and returned to the absorber 2, the separator 8 or the alkylation reactor 13. Any n-butane present may be removed through line 18 and disposed of through line 19 or charged to an isomerization unit 21 through line 20. The effluent from the isomerization unit 21 may be returned to the

11

System through line 22 to be added to the recycle isobutane from line 17. Light hydrocarbons in the motor fuel and/or aviation fuel boiling range are withdrawn from the separation unit 15 through line 23 and heavy hydrocarbons boiling above the motor fuel boiling range are withdrawn through line 24.

Example

A hydrocarbon stream containing mostly ethylene and methane together with smaller amounts of hydrogen, ethane, propylene, and propane, is counter-currently contacted at 30° F. and 750 p. s. i. with isobutane in an absorption tower. A gaseous mixture containing mainly hydrogen and methane is withdrawn at the top of the tower, and a liquid mixture of isobutane and ethylene containing minor proportions of ethane, propylene and propane is withdrawn from the bottom. The mol ratio of isobutane to ethylene in the latter mixture is approximately 8:1.

The isobutane-ethylene mixture is then passed through a catalyst chamber filled with a polymerization catalyst having the composition 1.5 per cent nickel oxide, 90 per cent silica gel, and 8.5 per cent alumina. Conditions for this treatment are: temperature, 120° F.; pressure, sufficient to maintain liquid phase; space velocity, 2 liquid volumes per volume of catalyst per hour. Approximately 70 per cent of the ethylene is polymerized, and of this amount approximately 80 per cent is converted to butylenes. The polymerization effluent is passed to a fractionation column from which ethane, unconverted ethylene, propylene, and propane are removed as an overhead fraction and recycled to the absorption tower.

The kettle product from the fractionator is passed to an alkylation reactor provided with a motor-driven stirrer and is intimately contacted with an equal volume of anhydrous hydrofluoric acid. The alkylation conditions are: temperature, 100° F.; pressure, sufficient to maintain the reactants in the liquid phase; contact time, 10 min.; mol ratio of isobutane to olefin, at least 16:1; acidity of the acid phase, 90 per cent. The effluent from the alkylation reactor is passed to a settler in which it separates into an acid phase, which is recycled to the alkylation reactor, and a hydrocarbon phase. Dissolved hydrofluoric acid is removed, as a minimum-boiling azeotropic mixture with isobutane, from the latter phase by distillation. Organically combined fluorine is removed by contacting the acid-free hydrocarbon phase with calcined bauxite at about 180° F. The substantially fluorine-free hydrocarbon phase is then passed through a series of fractionators from which the following fractions are obtained: a fraction, comprising chiefly isobutane, which is recycled to the absorption tower; a fraction, comprising hydrocarbons in the motor fuel boiling range, chiefly octanes, which is withdrawn as the main product of the process; and a fraction, comprising hydrocarbons that boil above the motor fuel range, which is withdrawn from the system.

I claim:

1. A process of converting normally gaseous olefin comprising mainly ethylene contained in a gaseous mixture containing other normally gaseous components into heavier hydrocarbons having molecular weight and boiling point in the motor and aviation fuel range which comprises absorbing said olefin comprising mainly ethylene from said normally gaseous mixture in liquid isoparaffin in an absorption zone while allowing other

12

normally gaseous components to pass through undissolved, withdrawing the resulting solution of olefin in liquid isoparaffin from the absorption zone and feeding it directly to a polymerization zone, effecting catalytic liquid phase polymerization of said olefin comprising mainly ethylene to higher-boiling olefin principally in the C₄ to C₆ range and mainly butylene in said polymerization zone, said isoparaffin serving as a diluent and enabling maintenance of liquid phase in said polymerization step, withdrawing the resulting mixture of said isoparaffin and said higher-boiling olefin and feeding it to an alkylation zone, and there alkylating said isoparaffin with said higher-boiling olefin to give heavier hydrocarbons having molecular weight and boiling point in the motor and aviation fuel range.

2. The process of claim 1 wherein the polymerization effluent is withdrawn from the polymerization zone and is subjected to separation into a C₃ and lighter fraction and a fraction of said isoparaffin and higher-boiling olefin which is employed as the feed to said alkylation step.

3. The process of claim 1 wherein said liquid isoparaffin is supplied to the top of said absorption zone in an amount such as to give a mole ratio to olefin in the gaseous mixture fed to said absorption zone of at least 2:1.

4. The process of claim 1 wherein the bottom of said absorption zone is reboiled, the feed thereto is supplied at an intermediate point therein, said liquid isoparaffin is supplied to the top thereof in an amount such as to give a mole ratio to olefin in the feed of at least 2:1, the overhead gases are cooled to effect condensation of at least the major portion of the C₄ content thereof and the resulting condensate is fed to the top of the absorption zone as reflux therefor.

5. The process of claim 1 wherein said polymerization is effected with a solid catalyst comprising nickel oxide supported on a carrier and activated by heating in an oxygen-containing atmosphere at a temperature of between 400 and 700° C.

6. The process of claim 1 wherein said olefin consists essentially of a major proportion of ethylene and a minor proportion of propylene and is converted substantially to butylene and amylenes in said polymerization step.

7. A process of converting ethylene contained in a normally gaseous mixture containing other normally gaseous components into branched chain octane which comprises absorbing said ethylene from said normally gaseous mixture in liquid isobutane in an absorption zone while allowing other normally gaseous components to pass through undissolved, withdrawing the resulting solution of ethylene in liquid isobutane from the absorption zone and feeding it directly to a polymerization zone, effecting catalytic liquid phase polymerization of said ethylene to butylene as the principal reaction in said polymerization zone, said isobutane serving as a diluent and enabling maintenance of liquid phase in said polymerization step, withdrawing the resulting mixture of said isobutane and polymer including butylene from said polymerization zone and feeding it to an alkylation zone, and there alkylating said isobutane with said butylene with an inorganic acid catalyst selected from the group consisting of substantially anhydrous hydrofluoric acid and concentrated sulfuric acid to give branched chain octanes.

8. A process of converting ethylene contained in a normally gaseous mixture containing meth-

75

ane and hydrogen into branched chain octanes which comprises absorbing said ethylene from said normally gaseous mixture in liquid isobutane in an absorption zone while allowing other normally gaseous components including the methane and hydrogen to pass through undissolved, withdrawing the resulting solution of ethylene in liquid isobutane from the absorption zone and feeding it directly to a polymerization zone, effecting catalytic liquid phase polymerization of said ethylene to butylene as the principal reaction in said polymerization zone, said isobutane serving as a diluent and enabling maintenance of liquid phase in said polymerization step, withdrawing the resulting mixture of isobutane and butylene from said polymerization zone and feeding it to an alkylation zone, and there alkylating said isobutane with said butylene with an inorganic acid catalyst selected from the group consisting of substantially anhydrous hydrofluoric acid and concentrated sulfuric acid to give branched chain octanes.

9. The process of claim 8 wherein said polymerization is effected with a solid catalyst comprising nickel oxide supported on a carrier and activated by heating in an oxygen-containing atmosphere at a temperature of between 400 and 700° C.

10. A process of converting ethylene and propylene contained in a normally gaseous mixture containing methane and hydrogen into alkylate in the motor and aviation fuel range of molecular weight and boiling point which comprises absorbing said ethylene and propylene from said normally gaseous mixture in liquid isobutane in an absorption zone while allowing other normally gaseous components including the methane and hydrogen to pass through undissolved, withdrawing the resulting solution of ethylene and propylene in liquid isobutane from the absorption zone and feeding it directly to a polymerization zone, effecting catalytic liquid phase polymerization of ethylene and propylene predominantly to butylene and amylene by simple and inter-polymerization as the principal reaction in said polymerization zone, said isobutane serving as a diluent and enabling maintenance of liquid phase in said polymerization step, withdrawing the resulting polymerization effluent, separating C₄ and lighter components from a mixture of isobutane and the polymer formed in said polymerization step and feeding said mixture of isobutane and polymer to an alkylation zone, and there alkylating said isobutane with said polymer with an inorganic acid catalyst selected from the group consisting of substantially anhydrous hydrofluoric acid and concentrated sulfuric acid to give heavier hydrocarbon in the motor and aviation fuel range of molecular weight and boiling point.

11. The process for the preparation of an alkylate comprising principally branched chain oc-

tales from ethylene contained in cracked gas containing same in dilute form in admixture with hydrogen and methane together also with some ethane and a small amount of propylene relative to the ethylene, said gas being free from C₄ and heavier components, which comprises absorbing the ethylene and propylene from said gas by intimately countercurrently contacting said gas in a vertical scrubbing zone with liquid isobutane in an amount such as to give a mol ratio of isobutane to ethylene plus propylene in said gas of from 2:1 to 10:1 at a top temperature below 40° F. and a pressure of from 700 to 800 pounds per square inch gauge and thereby effecting solution of substantially all of said ethylene and propylene in said gas in said isobutane while causing the hydrogen and methane to pass through undissolved, passing the resulting liquid isobutane containing dissolved ethylene and propylene directly to a catalytic polymerization zone and there effecting liquid phase polymerization of ethylene to butylene and inter-polymerization of propylene with ethylene to amylene as the principal reactions, effecting said polymerization at a temperature of from 24 to 150° C. with a solid catalyst consisting of nickel oxide supported on a carrier and activated by heating in an oxygen-containing atmosphere at a temperature of from 400 to 700° C., the isobutane serving as a diluent and enabling the maintenance of liquid phase in the polymerization step, fractionally distilling the polymerization effluent to separate same into a fraction of the material lighter than C₄ hydrocarbons and a fraction containing the isobutane and the butylene and the small amount of amylene formed in said polymerization step, passing said last-named fraction to an alkylation step and there alkylating said isobutane with said butylene and amylene with an alkylation catalyst composed of an inorganic acid which is incapable of effecting alkylation of isobutane with ethylene, thereby forming alkylate comprising principally branched chain octanes, and recovering said alkylate comprising branched chain octanes from the alkylation effluent as the product of the process.
